United States Patent Office

Des. 206,334
Patented Nov. 29, 1966

206,334

VELOCIPED

John W. Ryan, Bel Air, and Gerald W. Schmidt, Tarzana,
Calif., assignors to Mattel, Inc., a corporation of Cali-
fornia

Filed June 2, 1966, Ser. No. 2,521

Term of patent 14 years

(Cl. D34—15)

Fig. 2

Fig. 1

FIGURE 1 is a left-hand side elevational view of a velocipede showing our new design;

FIGURE 2 is a rear end elevational view of the design;

FIGURE 3 is a plan view of the design; and

FIGURE 4 is a perspective view of the design looking in from the front on the side opposite that shown in FIGURE 1.

We claim:

The ornamental design for a velocipede, as shown.
